X-RAY DRYING RACK OR THE LIKE

Henrietta M. Horvath, 221½ Justice St.,
Fremont, Ohio 43420

Filed June 5, 1972, Ser. No. 260,048

Term of patent 14 years

Int. Cl. D24—01
U.S. Cl. D83—1 H

FIG. 3

FIG. 1

FIG. 2

FIG. 4

FIG. 1 is a perspective view of a X-ray drying rack showing my new design;

FIG. 2 is a cross section taken on line 2—2 of FIG. 3;

FIG. 3 is a perspective view of the drying rack with portions omitted for clarity of illustration; and

FIG. 4 is a modified embodiment of the rack disclosed in FIG. 3.

I claim:

The ornamental design for an X-ray drying rack or the like, substantially as shown and described.
